Inventor:

Daniel Keefer

United States Patent Office.

DANIEL KEEFER, OF ATTICA, INDIANA.

Design No. 3,787, dated December 14, 1869.

DESIGN FOR A MASONIC ORNAMENT.

The Schedule referred to in these Letters Patent and making part of the same

To all whom it may concern:

Be it known that I, DANIEL KEEFER, of the city of Attica, in the county of Fountain, in the State of Indiana, have originated and designed a new Masonic Ornament, of which the following is a full, clear, and exact description, reference being had to the accompanying drawings, making part of this specification.

The nature of my invention or design simply consists in the grouping together of the square, the compass, the trowel, and the letter **G**, with a transverse board or mantel.

I will describe it more particularly by the accompanying photograph.

A B is the common square.

C D E, the compass.

P, the trowel.

x y, a small mantel, or board, placed at right angles to the large letter **G**, confined by the compass and square.

What I claim as my invention, and desire to secure by Letters Patent, is—

The design, or manner of grouping the square, the compass, the trowel, the letter **G**, and the board or mantel, fastened to the same, and at right angles thereto, as shown by the photograph herewith.

DANIEL KEEFER.
